Primary Examiner—Martie Thompson*Attorney, Agent, or Firm*—Peter G. Dilworth; Rocco S. Barrese; Joseph J. Catanzaro[57] **CLAIM**

The ornamental design for a writing instrument, as shown and described.

DESCRIPTION

FIG. 1 illustrates a front, bottom and right side perspective view of a writing instrument showing my new design, with the writing tip in the retracted position; FIG. 2 illustrates a front, top and left side perspective view thereof;

FIG. 3 illustrates a bottom end view thereof;

FIG. 4 illustrates top end view thereof;

FIG. 5 illustrates a front elevation view thereof;

FIG. 6 illustrates a side elevation view thereof;

FIG. 7 illustrates a rear elevation view thereof; and,

FIG. 8 illustrates a rear elevation view of the writing instrument with the writing tip in the extended position.

FIG. 1

FIG. 2

FIG. 3

FIG. 4

FIG. 8

FIG. 7

FIG. 6
